Specification of Letters Patent.

Patented Feb. 2, 1915.

Application filed May 15, 1905. Serial No. 269,414.

To all whom it may concern:

Be it known that I, WILLIAM E. NICKERSON, of Cambridge, in the county of Middlesex and State of Massachusetts, have invented certain new and useful Improvements in Grinding-Machines, of which the following is a specification.

This my invention relates to a machine for grinding and sharpening blades or other articles requiring great accuracy and fineness of finish.

The primary objects of my invention are to produce a machine for grinding extremely thin hardened steel blades to the finest possible edge without springing the same out of shape. These results are secured by means of the following novel features: First, the application of a reciprocating cross motion of the grinding element of a relatively high amount to the rotary movement of said grinding element producing thereby cutting scratches on the blade bevel of high angle to the edge. Second, an independent equalized pressure applied to the blade preventing the same from springing out of shape. Third, the pivoting of the work-holder automatically adjusting the bevel of the blade to the same plane as the shaft of the grinding wheel and directly over the center thereof, so that a change in the diameter of the grinding wheel by reason of wear or otherwise will not affect the angle of bevel of the blade.

Various other objects and novel features of this device will appear in the following description and will be particularly pointed out in the claims.

In the accompanying drawings which illustrate a construction embodying my invention, Figure 1 is a perspective view of a machine embodying my invention. Fig. 2 is a side elevation of the device. Fig. 3 is a plan view of the machine. Fig. 8¹ is a transverse view on the line 1-1 of Fig. 3 showing the method of plumbing the standard C¹ and also the manner whereby the frame N¹ rocks the frame N' through the medium of the said screw V¹. Fig. 4 is a front elevation showing the work out of contact with the grinding wheel. Fig. 5 is a front elevation showing the holder adjusted to position and the work being operated upon. Fig. 6 is an elevation showing the

lever rolls mounted between the collars on the grinding wheel spindle. Fig. 7 is a side elevation of the pivoted adjusting bars of the holder showing the horizontal or working position, the dotted lines showing the idle or non-operating position. Fig. 8 represents a blade showing the cutting scratches on the bevel of high angle to the edge. Fig. 9 represents a blade, the bevel showing usual ordinary cutting scratches. Fig. 10 is an elevation showing blade mounted in holder, the application of the pivoted pressure bar thereon and the relative adjustment of the blade bevel to the grinding wheel. Fig. 11 is an end elevation of the spring holder attachment. Fig. 12 is a plan view of the same. Fig. 13 is a side elevation of the same. Fig. 14 is a side elevation showing the blade inserted. Fig. 15 is a side elevation showing the holder open. Fig. 16 is a plan view of the hanger and regulating mechanism. Fig. 17 is a front elevation of the same showing clutch thrown out of position, and Fig. 18 is an end elevation of the same.

Referring now to the drawings in detail in which like characters of reference are employed to designate similar parts throughout the several views, a bed-plate A, is illustrated, upon which various portions of the mechanism are mounted. The abrasive element is shown supported by a plate B, secured to the plate A, by bolts O. The plate B carries a pair of standards B¹, B² in which standards is mounted a spindle B³. The spindle B³ is mounted for rotation and reciprocation. A sleeve C, surrounds the spindle B³ and is slidably mounted in standard B². The sleeve is prevented from longitudinal movement relative to the spindle by being held between a pair of collars C², C³, fast upon the spindle B³. The sleeve is held from rotary movement relative to the bearing B² by means of a pin O¹, carried by the sleeve and engaging a bar C⁵, carried by standard B¹. The engagement between elements C¹ and C⁵ is such as to permit the sleeve to move longitudinally with the spindle B³ and through the bearing B², but prevents its rotation relative to the bearing B². By the interposition of the sleeve C between the spindle and the bearing, the bearing is subjected to wear in but one direction,

namely in the direction of the reciprocation of the sleeve C, and the spindle is subjected to wear in but one direction, namely, that caused by its own rotation. The avoidance of the crossing of lines of wear saves the life of the parts and reduces friction. The abrasive element, in the present illustration, the grinding-wheel B⁴, is fast on one end of the spindle B³. The grinding-wheel is shown securely held between a pair of collars B⁷ and B⁸. The collars B⁷ and B⁸ and the grinding-wheel are set together by means of a thumb-screw B⁹, thus effecting means for the ready removal of a worn-out wheel and its replacement by a new one. The spindle B³ will be rotated intermittently by means of a belt passing over a pulley B⁶, held to the spindle by means of a set-screw B⁵. The mechanism for intermittently operating the belt will presently be described. During the rotation of the grinding-wheel, it is also reciprocated. A lever D, is illustrated for performing this work. The lever D is mounted upon an upper right D¹, held in place thereon by means of a cotter-pin D⁵, and carries at its forked end a pair of pins D², D³ which are provided with rollers D⁴, which engage the collar C³ and a collar C⁶, pinned to the spindle B³. The lever D is rocked for the purpose of reciprocating the grinding-wheel by means of a wrist-pin E⁸ mounted upon a crank-disk E⁵, which is fast on a shaft E³, which shaft is rotated in its bearings E¹, E², by means of a pulley E⁴ fast upon it, from mechanism presently to be described. The bearings E¹, E², are in the nature of standards supported by a plate E, mounted upon the bed-plate. A connecting-rod F, connects the crank-wrist-pin and the free end of lever D. A block F¹, is mounted on the wrist-pin E⁸, and is shown held in position by means of a washer and cotter-pin F⁶. This block is connected to one forked end of the connecting-rod F, by means of bolts F², F³. A block F⁴, is mounted on a wrist on the free end of the lever D, and is secured to the other forked end of the connecting-rod F, by means of bolts F⁵, F⁶. A suitable washer and cotter-pin F⁷ is illustrated for securing the block F⁴ in position. Thus it will be seen that upon the rotation of the shaft E³, the spindle B³, will be reciprocated, which will cause a reciprocation of the grinding-wheel B⁴, such reciprocation taking place during the rotation of the grinding-wheel.

After the blade has been properly positioned in its holder, suitable mechanism will be brought into play for bringing the blade into proper engagement with the grinding-wheel, and this movement is utilized for inaugurating the rotation and reciprocation of the grinding-wheel B⁴. In the present illustration the belts connected with the pulleys B⁸ and E³, run over pulleys T, T'

which are fast upon a shaft S', supported in suitable hangers S², S³, carried by a base-plate S, and which shaft in the present instance is shown driven by a belt Z, from a pair of fast and loose pulleys S⁷ and S⁸. Fast upon the shaft S', is a worm T², which engages a worm-gear T³, and rotates this gear during the rotation of the shaft E³ and spindle B³. The belt-shipper is shown comprising a belt-engaging member mounted upon the reciprocatory shaft T⁹. The belt is held normally on the loose pulley S⁸, by the action of the spring U⁶, which is attached to hanger S² and to arm T⁷ rigidly attached to slidable shaft T⁹, which the latter has a tendency to move in a direction to cause the belt-shipper to ship the belt on to the loose pulley S⁸. The belt-shipper is moved into the active position by means of a bell-crank lever U¹⁰ pivoted on the shaft T⁴, of the worm-gear T³, and having means of connection U², with the tripping-rod V. A clutch-member or drum T⁵, is mounted upon the shaft T⁴, and has a friction-face abutting a friction-face provided on the worm-gear T². A friction-disk T⁶ is interposed between these members. The frictional contact is produced by means of a suitable compression-spring T⁸. Drum T⁵ holds the belt-shipper in such position that the belt will remain on the fast pulley. Openings T¹⁰ are provided in the drum to receive the end of the arm T⁷ at predetermined intervals and permit the belt-shipper to move and ship the belt on to the loose pulley responsive to the spring U⁶. The member T⁷ is fast with the spindle T⁹, controlling the belt-shipper and is prevented from rotation upon the axis of the spindle T⁹ by having an extending arm T¹¹ forked to engage the shaft S'. Fast with the member T⁷ is a lug or engaging finger U⁸ which is engaged by the forked-end U⁵ of the bell-crank-lever U¹⁰ pivoted upon the shaft T⁴ of the worm-gear T³. The other end U², of the bell-crank-lever U¹⁰, is connected with the actuating-rod V. By drawing the actuating-rod V downwardly in the present illustration, the member T⁷ and its associated parts, including the belt-shipper and belt, will be moved to the left in Figs. 16 and 17 and the belt moved to the fast pulley which will inaugurate the movement of the worm-gear T² and the associated drum T⁵, which drum will then be interposed in the path of movement of the member T⁷, responsive to the spring U⁶ thus preventing a return of the belt to the loose pulley. Upon the movement of the drum sufficient to bring one of the openings T¹⁰ into registry with the member T⁷, the shipper and associated parts will be moved by spring U⁶ toward the right in Figs. 16 and 17 which will cause the arm U² of the bell crank lever to rise and draw upwardly on the actuating-rod V. The object of this

portion of the device is to permit a predetermined amount of movement of the grinding-wheel at each operation. After a blade is placed in the holder, mechanism will be 5 actuated for bringing the blade into proper relation to the grinding-wheel, which will draw down upon the actuating-rod V and inaugurate the movements of the grinding-wheel. Upon a predetermined amount of 10 grinding-wheel movement, determined by the positioning of the openings T¹⁰, the upward movement of the arm U², drawing upwardly on the actuating-rod V, will trip the mechanism for releasing the blade-holder and cause this to be withdrawn from the 15 grinding-wheel. The detail description of this mechanism will appear in its proper place.

The blade-holder is shown comprising a 20 pair of jaws W³, W⁴, held together upon the work by means of springs W², W². These jaws are carried by a shank K¹⁰, one of the jaws being shown fast thereon and the other pivoted at W⁵. An actuator W' is provided, by which the jaws may be separated 25 against the tension of the springs W², for the purpose of permitting the removal and insertion of the blades W. One of the jaws may be provided with pins W⁶, for 30 entering holes in the blade, which pins in practice may pass through the other jaw.

One of the objects of this invention is to produce the same angle and the same results upon the blade, whether this is presented to 35 a wheel which is new and of its maximum radius, or whether it is presented to a wheel which has been considerably worn away and is of a radius small relatively to the radius of the wheel when new. To accomplish this 40 successfully the blade must be presented to the wheel at a proper angle and on a proper portion of its periphery, and be maintained in a practically horizontal plane. The mechanism herein illustrated for effecting 45 this movement of the blade comprises a series of linkages or levers.

An angle-plate G, is shown mounted on the bed-plate A. Such plate G, is provided with a face for resting upon the top of the 50 bed-plate A, and a face for engaging the edge bed-plate which runs transversely of the axis of the spindle B³. This plate G, is provided with longitudinal slots G', in which suitable tap-bolts may be mounted 55 for permitting the adjustment of this plate toward and from the shaft or spindle B³. The plate G, is for the purpose of supporting the mechanism which carries the blade-holder. The angle-plate G, has mounted 60 upon it a pair of supports G², G³, in which is mounted a shaft H, which is held from rotation by means of set-screws H². A frame H³, is mounted for oscillation on the shaft H. The frame H³ is somewhat in the nature 65 of a yoke having its ends mounted outside

the bearings G², G³. The back end of the frame H³ is provided with a sector-shaped extension H⁴, which by means of a cord H⁶, supports a weight H⁵, for the purpose of counter-balancing the frame and raising the 70 front end of the same. The limit of movement of the frame upwardly at the front end and downwardly at the back end is adjusted by means of a set-screw H¹⁰, which will engage the bearing G⁴, which is fixed relative to the axis H of this frame. The front end of the frame H³, carries the work-holder and is provided with a pair of pivot-screws K², locked in position by means of nuts K³. Upon the pivot screws is mounted the body-member of the standard K, which body-member is provided with a face-plate K⁰, which face-plate is maintained in a substantially vertical plane and transverse of the axis of rotation of the grinding-wheel. A 80 holder K⁸, is supported upon this face-plate and is adjustable thereon about its axis in the plane of plate K⁰, the adjusting device being shown as a pair of eccentrics M, which can be moved into proper position and locked by means of set-screws M'. This 85 holder K⁸ is provided with a suitable recess for receiving the shank K¹⁰, of the blade-holder. A suitable spring-lock comprising a spring K¹¹ carrying a detent K¹² for entering a circumferential groove K¹³ in the shank K¹⁰ is provided for holding the shank in position in the holder K⁸. A standard G¹⁰ approximately the height of the standard K is held fast upon the non-rotary spindle H, by means of a set-screw H⁹, this 90 standard having a bifurcated lower end G¹⁴ which straddles the base of the supports G² and G³ permitting pivotal adjustment of the standard on the spindle H by the set-screw H⁸, set-screws H⁸ being provided in the bifurcated portion G¹⁴ for plumbing the standard. Said standards are, at the tops, connected by a link K⁴, which is mounted on the standard G¹⁰, by means of a pin K⁵, 100 and on the standard K, by means of a pin K⁷. Upon the rocking of the frame H³, the blade-holder would normally move through the arc of a circle, but by means of the connection between the standards K and G¹⁰, the standard K is rocked on the pivot-pins K², to such an extent that the blade-holder and the blade will be maintained parallel with the surface of the abrasive element during their movement toward and 105 from the grinding-wheel in a right line radially of the axis of rotation thereof. The workholder is capable of oscillation on the shank K¹⁰ in the recess of the holder K⁸ thus enabling the 110 blade to accommodate itself to any irregularities or vibration of the parts as the blade is moved into engagement with the grinding-wheel and compensating for any 115 errors in the adjustment of the parts. 120

A frame N in the nature of a yoke, is mounted on the non-rotary spindle H, the ends of this frame being shown disposed outwardly of the adjacent ends of the frame or yoke H³. The front bar of this yoke is disposed underneath the end members of the yoke or frame H³. One of the end members of the yoke or frame H³, carries an adjustable abutment in the form of a set-screw 5 H', which upon the rising of the frame N will be engaged for the purpose of raising the front end of the frame H³ and thereby the workholder.

The plate G carries a bearing G⁴ disposed 15 transversely of the fixed shaft H. A shaft G⁵, is mounted in the bearing G⁴. A cam-wheel G¹¹ is fast on this shaft and engages an antifriction roller P², carried by the frame N. The shaft G⁵ has fast upon it a 20 segmental lever G⁸, which carries by means of a suitable cord a weight G⁹. This weight is for the purpose of effecting the raising of the work-holder. The frame N is provided with a series of adjustable weights N' for 25 the purpose of pressing the frame N down.

A lever R, is supported on a shaft R³, and carries a roller R' in the path of movement of the cam-wheel. An actuator in the form of a finger-key G⁷ is fast with the shaft G⁵. 30 When it is desired to render the mechanism active upon the grinding element and bring the work into engagement with the same, the actuator G⁷ will be depressed, permitting the roller P² to run down the face of the cam, which will permit the frames N and H³ to be lowered at the same time. The appropriate surface of the cam G¹¹ will engage the roller R' and depress the lever R, which is connected with the actuator-rod V, drawing this rod down and so actuating the parts which move the belt-shipper into a position to cause the belt to be shipped on to the fast pulley. The cam-wheel is provided with a projection G⁶, which, upon the down 40 movement of the actuator G⁷, will be brought into a position to engage a detent or pawl R², which is mounted on the spindle R³. A coil-spring surrounds the spindle R³ and engages a pin R⁴ at one end and at the other 45 end engages a lug R⁵ on the pawl R² for forcing this into its active position, that is, forcing it into such a position that upon a movement of the actuator and cam-lever for starting the mechanism, the pawl will engage the 50 abutment G⁹ and hold the various parts in their active position until the opening T¹⁰ is presented to the member T¹, when the belt-shipper will move and at the same time raise the member U² of the bell-crank-lever, 55 which will draw up on the actuator-rod V, and rock the arm R, and pawl R², against the action of its spring, the detent R¹² carried by the lever R simultaneously engaging the detent R¹¹ on the pawl R² and releasing 60 the cam-wheel, which will raise the frame N 65

and the frame H³, the weight G⁹ being of sufficient strength in connection with the weight H⁵ to effect this elevation.

The speed of reciprocation of the grinding-element will be so adjusted and timed 70 relative to the speed of rotation thereof that while the work is being engaged by the grinding-element, there will be the resultant of a compound movement which will produce a series of scratches disposed at an 75 angle to the cutting edge, and owing to the fact of the reciprocatory movement, the grinding scratches will cross each other transversely upon the beveled edge which is ground. The production of scratches is in 80 the employment of customary abrasives inevitable. By so controlling the angle of abrasion that the scratches made by one wheel traverse will transversely cross those made by the previous traverse these latter 85 will be more completely obliterated than when the intersection of the successive scratches is at a small angle or if the scratches are all disposed in the same direction. The grinding element will run in a 90 suitable bath which may be provided by a tank R⁶, supported on bars R', R⁸.

It will be seen that the support for the holder will, by means of the eccentrics M, M, be adjusted about a pivot, in the present 95 illustration in the nature of a set-screw M². After the adjustment has been effected the pivot screw may be set down to assist in the holding of the parts in their position of adjustment. The adjustment about this 100 pivot-point M² is in a direction transverse to the pivotal axis of the frame, H³ and, in the present instance is substantially parallel with the axis of rotation and the line of reciprocation of the grinding element. Adjustment of this support toward and 105 from the axis in a direction transverse to the pivot M² may be effected by means of a set-screw M⁴. It will be seen that the holder proper for the work is oscillatory upon the 110 axis substantially transverse to the axis M², upon which the support is adjustable and substantially parallel with the axis upon which the frame H³ is oscillatory. This is for the purpose, as was above stated, of permitting the work to accommodate itself and 115 compensate for errors in the adjustment of the mechanism, or those errors which may occur from vibration of the parts one relative to the other.

The work will be so presented to the grinding element that it will move or rather its edge will move in a plane which is radial of the grinding element. By this means the same bevel will be imparted to the blades, 120 whether they are presented to a grinding-wheel of relatively large or relatively small diameter. This is so that as the wheel wears away the quality of the work will not be impaired.

During the grinding operation it is desirable, when very thin work is being acted upon, as for instance thin razor blades, that the edge of the work acted upon be supported independently of the support afforded by the workholder. In the present illustration a pressure-plate or pressure-bar P , is provided for this purpose, which is movable in the plane in which the edge of the work is movable. This pressure-plate is carried by an extension of one of the arms of the frame N , which arm is provided with a face-plate N^1 having a face substantially transverse to the face K^1 , and to this face is pivoted a slotted plate N^4 , by means of a suitable bolt N^3 , the slot of which receives the pressure-plate or bar P , which is mounted therein and maintained in adjusted position by the thumb-screw P' . This plate P when properly adjusted by means of the thumb-screw P' extends longitudinally of the blade as shown in Fig. 1, bearing upon the edge of the blade and exerting an equalized pressure thereon from end to end so that the blade cannot spring or bulge out of shape during the grinding operation, insuring an even treatment of the entire cutting edge of the blade. The plate N^4 has fast with it a standard N^5 , which is connected by means of a link N^6 , with a standard N^7 , fast with the non-rotatable spindle H . The connection between the frames or yokes H^2 and N permits a certain amount of independent movement one relative to the other. This will permit the weights N^8 , mounted upon the spindle N^7 , to become active upon the pressure-plate P and cause the same to engage the edge of the blade at the side opposite that which is being ground and hold it in intimate contact with the grinding element throughout its entire length.

Although but one form of my invention has been illustrated and described, it will be apparent that changes may be made without departing from the spirit of my invention.

Having thus described my invention what I claim as new and desire to secure by Letters Patent is.

1. In a grinding machine, a grinding element, a work-carrying element, mechanism for presenting work in the work-carrying element to the grinding element, a pressure bar independent of said mechanism and work carrying element for applying pressure to the work and means automatically operating to bring said pressure bar into contact with the work upon the said mechanism for presenting the work becoming operative; means for adjusting said pressure bar upon work mounted in said work-carrying element.

2. In a grinding machine, a grinding element, a work-carrying element, mechanism for presenting work in the work carrying

element to the grinding element, a pressure bar independent of said mechanism and work carrying element for applying pressure to the work and means automatically operating to bring said pressure bar into contact with the work upon the said mechanism for presenting the work becoming operative; and means located upon said pressure bar for equalizing the distribution of pressure upon said work.

3. In a grinding machine, a grinding element, a work-carrying element, mechanism for presenting work in the work-carrying element to the grinding element, a pressure bar independent of said mechanism and work carrying element for applying pressure to the work and means automatically operating to bring said pressure bar into contact with the work upon the said mechanism for presenting the work becoming operative, and pivoted means located upon said pressure bar for equalizing the distribution of pressure upon said work.

4. In a grinding machine, the combination with a grinding wheel and means for rotating the same and for simultaneously reciprocating it in the direction of its axis, of a blade holder support and a pressure bar support mounted to turn independently on a common axis extending at right angles to the axis of said wheel, a blade-holder carried by the blade holder support and adapted to present the edge of a blade to the grinding wheel, in parallelism with the axis of the latter, and a pressure bar carried by the pressure bar support and adapted to hold the edge of the blade against the wheel.

5. In a grinding machine, the combination with a grinding wheel and means for rotating the same, of a blade holder located in position and adapted to present the edge of a blade to said wheel, in parallelism with the axis of the latter, and provided with a laterally extending stem, a blade holder support on which said stem is journaled, said support being movable toward and away from said wheel in a plane transverse with respect to the axis of the wheel, and a pressure bar movable to and from the wheel independently of the blade holder and located in position and adapted to hold the edge of the blade against said wheel.

6. In a grinding machine, the combination with a grinding wheel and means for rotating the same, of a blade holder located in position and adapted to present the edge of a blade to said wheel, a counter-balanced frame to which said blade holder is secured, said frame and blade holder being movable toward and from the wheel, a weighted pressure bar frame mounted to move toward and from the wheel, independently of the blade holder, and provided with a pressure bar located in position and adapted to press the blade against the wheel, means for

raising and lowering said pressure bar frame, and adjustable means between the pressure bar frame and the counter-balanced frame constructed and adapted for controlling the movements of the latter toward and from the wheel by the corresponding movements of the former.

7. In a grinding machine, the combination with a grinding wheel, of a work holder, a pivotally mounted presser for the work, and means for maintaining the operative surface of the presser in alignment with the surface of the grinding wheel.

8. A grinding machine having a grinding element, a work-holder, and timing mechanism for automatically stopping the operation of said grinding element and shifting the work holder upon a predetermined amount of movement of the grinding element.

9. A grinding machine having a grinding element, a work-holder, means for moving the work-holder into operative position adjacent the grinding element and for simultaneously starting the operation of the grinding element, and means for automatically stopping the operation of the grinding element and moving the work-holder away from said grinding element.

10. A grinding machine having a grinding element, a pivotally-movable frame, a work-holder support pivotally connected with said frame for movement on an axis transverse of the pivotal axis of the frame, a work-holder pivotally connected with said work-holder support for movement on an axis parallel with the pivotal axis of the frame, and means for moving the work holder toward and away from the grinding element and simultaneously starting and stopping the operation of said grinding element.

11. A grinding machine having a rotary grinding element, a frame pivotally movable about a fulcrum at right angles to the axis of the grinding element, a work-holder support pivotally connected with said frame, the fulcrum of said work-holder support being parallel with the axis of said grinding element, a work-holder pivotally connected with said work-holder support, and timing mechanism for automatically stopping the

operation of the grinding element upon the completion of a predetermined movement of said element.

55

12. A grinding machine having a grinding element, a pivotally-mounted frame, a work-holder connected with said frame, a gravity-actuated presser-bar located in position for acting directly upon work in said holder, and means for raising and lowering said frame and presser-bar.

13. A grinding machine having a grinding element, a pivotal frame, a work-holder connected with said frame, a gravity actuated presser element, reciprocating and rotating mechanism for said grinding element, a manually-operable device for lowering said work-holder and presser element and for starting said reciprocating and rotating mechanism, and means for automatically raising said work-holder and presser element and stopping said rotating and reciprocating mechanism.

75

14. In a grinding machine, the combination with a grinding wheel and means for rotating the same and for simultaneously reciprocating it in the direction of its axis, of a blade holder adapted to automatically present the edge of the blade to said wheel in parallelism with the surface of the latter, means for maintaining the entire surface of the edge of the blade being operated upon in intimate contact with the grinding wheel, and means for moving said blade holder toward and from said wheel in a plane defined by the edge of the blade and the axis of the wheel.

80

85

15. In a grinding machine, the combination with a grinding wheel, of a work holder, a pivotally mounted presser for the work, means carried thereby for engaging with and maintaining the work in intimate contact with the grinding wheel and means for maintaining said latter means in alignment with the surface of the grinding wheel.

90

In testimony whereof, I have signed my name to this specification in the presence of two subscribing witnesses, this eighth day of May, A. D. 1905.
